UNITED STATES PATENT OFFICE.

EDWARD E. CRAWFORD, OF BREMERTON, WASHINGTON.

WINDOW-STOP.

1,381,083.

Specification of Letters Patent. Patented June 7, 1921.

Application filed May 27, 1920. Serial No. 334,675.

To all whom it may concern:

Be it known that I, EDWARD E. CRAWFORD, a citizen of the United States, residing at Bremerton, in the county of Kitsap and 5 State of Washington, have invented certain new and useful Improvements in Window-Stops, of which the following is a specification.

The object of this invention is to provide 10 a simple, inexpensive and efficient device which may be readily applied to any window sash and by the use of which the opening of a window from the outside will be prevented, although the window may be 15 opened from the inside to a limited extent for ventilating purposes.

The invention is illustrated in the accompanying drawings, in which—

Figure 1 is a perspective view of a portion 20 of a window having the invention applied thereto;

Fig. 2 is an enlarged vertical section showing the operation of the invention;

Fig. 3 is a front elevation of a portion of 25 a window sash having the improved device applied thereto.

In the drawings, the reference numeral 1 indicates a portion of a window frame, 2 designates the upper sash and 3 designates 30 the lower sash, all of which parts may be of any desired dimensions and of the usual construction except as hereinafter specifically set forth.

In carrying out my invention, I form in 35 the inner face of the side bar of the upper sash a recess in which a casing 4 is snugly fitted. This casing may be of thin cast metal or may be stamped out of sheet metal as preferred, but in any event will present a 40 chamber 5 in which the stop or lock is mounted. The casing also presents a face plate 6 through the ends of which fastening screws or similar devices 7 may be inserted to secure the casing or frame in place. The 45 back wall of the casing is arcuate in its upper portion, as shown at 8, and in its lower portion presents an inclined web 9 from which depends a vertical wall 10, said vertical wall being spaced from the inner side 50 or face plate, as clearly shown in Fig. 2. The bottom end wall 11 of the casing is constructed with a recess or notch 12 to permit the insertion of a finger when it is desired to turn the lock or stop to its operative position. It will be readily understood of course, 55 that the face plate 6 lies flush with the inner

surface of the sash so that when the stop is in its inoperative position the sashes may be readily raised or lowered. Disposed transversely in the upper portion of the 60 casing concentric with the arcuate back wall 8 thereof is a pin or shaft 13 upon which is rotatably mounted a stop consisting of a flat-sided circular body 14 and a tangential dog or tooth 15. The body 14 and tooth 15 are of 65 such dimensions that the tooth may fit closely within the lower portion of the casing with the outer straight side thereof flush with the face plate when the device is in its inoperative position so that there will be no obstruction to the free movement of either sash. When it is desired to lock the sashes against 70 opening from the outside, the stop is turned to the position shown in Figs. 1 and 2, whereupon the tooth will project from the face 75 of the sash at a right angle thereto so that it will be adapted to impinge upon the upper cross bar of the lower sash and thereby limit the movement of both sashes. The body 14 of the stop is provided with a peripheral recess 16 and upon the back wall of the casing at the lower side of the arcuate portion 8 thereof is a transverse shoulder 17. A leaf spring 18 is secured at one end upon the peripheral face of the stop at the extremity of 80 the recess 16 and at the base of the tooth 15. The free end of this spring 18 is adapted to press outwardly and engage against the shoulder 17, as shown in Fig. 2, so that when 85 the stop has been turned to its operative position it will be held in said position until the sashes are closed sufficiently to give access through the front of the casing to the spring detent or pawl. When the tooth 15 is turned downwardly, the spring will ride 90 95 backwardly within the casing and will frictionally engage the back wall of the casing so as to hold the stop in its inoperative position.

Normally the device will be in its inoperative position. When it is desired to open a window for ventilating an apartment and permit it to remain open to an extent sufficient for ventilation but not sufficient to permit the entrance of a person from the outside, the lower end of the tooth 16 is engaged by the end of a finger inserted in the recess 12 and the stop is then swung to the position shown in Figs. 1 and 2 in which the outer flat tangential face of the tooth abuts 100 105 the upper flat tangential wall of the casing. Either sash may then be closed or opened 110

within the limit provided by the stop without further manipulation of the stop so that ventilation may be obtained but the entrance of an intruder will be prevented. When it 5 is desired to readjust the window so that either sash may be opened to its full extent, the sashes are first adjusted to clear the face plate 6 after which a slight pressure is exerted upon the free end of the spring 18 so 10 that its end will be released from the shoulder 17 and the stop is then swung downwardly so as to be housed within the casing.

It will be readily noted that I have provided an exceedingly simple and inexpensive 15 device which may be very easily manipulated and is highly efficient for the purpose for which it is designed.

Having thus described the invention, what is claimed as new is:

20 A device for the purpose set forth comprising a casing having an upper circular chamber with an upper tangential wall extending to the front face of the casing and a lower inclined tangential wall terminating

short of the face of the casing, the casing 25 being constructed to present a recess extending downwardly from the terminal of the lower tangential wall, a transverse shoulder at the upper terminal of the lower tangential wall, a stop pivotally mounted in the 30 upper portion of the casing and comprising a circular body concentric with the pivot, and a tooth projecting tangentially from said circular body and adapted to impinge against the upper tangential wall of the cas- 35 ing or to be housed within the downwardly extending recess, the circular body of the stop being provided with a peripheral recess, and a resilient detent secured at one end in the said recess and having its other 40 end free to engage the transverse shoulder on the lower tangential wall of the casing or to be housed within said peripheral recess and frictionally engage the rear arcuate wall 45 of the casing.

In testimony whereof I affix my signature.

EDWARD E. CRAWFORD. [L. S.]
